US00D941423S

(12) **United States Design Patent** (10) **Patent No.:** **US D941,423 S**
(45) **Date of Patent:** **** Jan. 18, 2022**

(54) **MISTING DEVICE**

(71) Applicant: **OMS Investments, Inc.**, Los Angeles, CA (US)

(72) Inventors: **Paul M. Havlovitz**, Dublin, OH (US); **Derek Jordan Recker**, Columbus, OH (US); **David Slade Simpson**, Worthington, OH (US); **Michael Thomas Kopczewski**, Orient, OH (US); **Jay F. Perkins**, Pickerington, OH (US)

(73) Assignee: **OMS Investments, Inc.**, Los Angeles, CA (US)

(**) Term: **15 Years**

(21) Appl. No.: **29/794,529**

(22) Filed: **Jun. 14, 2021**

Related U.S. Application Data

(63) Continuation of application No. 29/695,172, filed on Jun. 17, 2019, now Pat. No. Des. 922,523.

(57) **CLAIM**

The ornamental design of a misting device, as shown and described.

DESCRIPTION

FIG. 1 is a top isometric view of an embodiment of a misting device illustrating the new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top planar view thereof;

FIG. 7 is a bottom planar view thereof; and,

FIG. 8 is a bottom isometric view thereof.

The broken lines in the drawing views represent portions of the misting device that form no part of the claimed design.

1 Claim, 7 Drawing Sheets
